CLAIM

The ornamental design for a shoe, as shown and described.

DESCRIPTION

FIG. 1 is a front, right, and top perspective view of a shoe, showing my design.

FIG. 2 is a rear, left, and bottom perspective view thereof.

FIG. 3 is a right side view thereof.

FIG. 4 is a left side view thereof.

FIG. 5 is a rear view thereof.

FIG. 6 is a front view thereof.

FIG. 7 is a top plan view thereof; and,

FIG. 8 is a bottom plan view thereof.

First embodiment for a right foot shoe as shown in FIGS. 1 to 8; a second embodiment for a left foot shoe, which is a mirror image of the preceding embodiment, is also claimed but not shown.

1 Claim, 8 Drawing Sheets
